UNITED STATES PATENT OFFICE.

LAURA G. HARPER, OF ROCKFORD, ILLINOIS.

DESIGN FOR A COMBINED BOOK AND MAGAZINE STAND.

Application filed August 12, 1925. Serial No. 14,403. Term of patent 3½ years.

To all whom it may concern:

Be it known that I, LAURA G. HARPER, a citizen of the United States, residing at Rockford, in the county of Winnebago and State of Illinois, have invented a new, original, and ornamental Design for Combined Book and Magazine Stand, of which the following is a specification, reference being had to the accompanying drawing, forming part thereof.

In the drawing the figure is a perspective view of a combined book and magazine stand, showing my new design.

I claim:

The ornamental design for a combined book and magazine stand, as shown.

LAURA G. HARPER.
